Technical drawing of a leather belt with two buckles, labeled 9, 10, 7, 11, and Fig. 2.

Inventor:

11 Henry L. Ferris,
Big Dryuppath, S. C. Clinton & Miles,
Attison

UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

STALL CONSTRUCTION.

1,078,999.

Specification of Letters Patent. Patented Nov. 18, 1913.

Application filed March 15, 1912. Serial No. 683,997.

To all whom it may concern:

Be it known that I, HENRY L. FERRIS, a citizen of the United States, residing at Harvard, in the county of McHenry and 5 State of Illinois, have invented a new and useful Improvement in Stall Construction, of which the following is a specification.

My invention relates to certain new and useful improvements in stall construction, 10 and is fully described and explained in the specification and shown in the accompanying drawing, in which—

Figure 1 is a view of one of the series of stalls embodying my improved construction, 15 and Fig. 2 is a section on the line 2 of Fig. 1.

Referring to the drawings, 3 is a sill which will ordinarily lie along the line of separating the stall from the manger; 4 is a vertical upright forming a part of the barn 20 structure. At intervals along the sill, vertical posts 5 are erected to which and to the vertical post-member 4 the stall-sides may be secured in any desired manner.

6 is a horizontal bar of the stall end-frame 25 and 7 is an inverted U-shaped member attached thereto and therewith completing the end-frame. The lower bar 6 is longitudinally adjustable by means of brackets 8 attached to the vertical member 4 and to the 30 posts 5 of the series. A horizontal bar 9 is attached to the posts 5 of the series and to the vertical member 4 and thereon is mounted an adjusting bracket 10, which has a portion 35 embracing the horizontal bar 9 and a longitudinally-extending flange 11 having a series of perforations adapted to be engaged by ears 12 on the stall end-frame. By means of the adjusting brackets 8 and the adjusting bracket 10 the entire frame may 40 be moved longitudinally of the stall for the purpose of securing the now known desirable results of such adjustment. The stall end-frame, of course, carries a stanchion or other animal-fastening means as may be desired. 45

In the manufacture of stall-constructions in accordance with a unit system whereby any number of stalls may be arranged in series, several different constructions have 50 been devised by me in the past. Certain of these embody the use of the particular form of stall end-frame here shown. It is often found, however, that there are particular spaces in given barns lying between uprights, such as the uprights 4, which are al-

ready in position in the barn as a part of the frame-work thereof. These special spaces are of irregular and varying sizes which often do not accommodate themselves to stock sizes of stall parts which can be 60 made up, and it is for such positions that the present construction is more especially devised. The present stall end-frames can be made in two or three stock-sizes with their lower bars or members projecting at the 65 ends more than is likely to be needed. Any special or irregular space can then be divided into the requisite number of stall-panels by the erection of the vertical post in them and by merely sawing off the ends 70 of the straight projecting lower members of the stall end-frame, these can be brought to the proper lateral dimension. The upper part of the stall end-frame being supported at the middle on the horizontal bar 9 offers 75 no obstacle to this adjustment. If, as I have heretofore suggested, the stall end-frame be secured to the stall-sides by means engaging the sides of the stall end-frame, special sizes either of stall end-frames or of attaching 80 means will be required in each special case, but in the present instance a construction is arrived at whereby two or three stock sizes of stall end-frames can be fitted in proper multiples into any size space available. 85

I realize that considerable variation is possible in the details of the present construction and I do not intend to limit myself thereto, except as pointed out in the following claims in which it is my intention to 90 claim all the novelty inherent in the present construction as broadly as is permitted by the state of the art.

I claim as new and desire to secure by Letters Patent:

1. In a barn equipment, the combination with fixed vertical uprights forming part of the barn structure, of a stall-end construction adapted for erection between said uprights and comprising an upper horizontal member extending between the same, vertical posts adjustably connected to said upper horizontal member, a lower horizontal member adapted to be cut into suitable lengths to extend between the fixed uprights and the vertical posts adjacent their lower ends, a stanchion secured to said lower horizontal member, and an adjustable connection between the upper end of said stanchion and said upper horizontal member, 100 105 110

whereby said stall-end construction may be erected in spaces of varying widths between the fixed vertical uprights of the barn structure.

- 5 2. In a barn equipment, the combination with fixed vertical uprights forming part of the barn structure, of a stall-end construction adapted for erection between said uprights and comprising an upper horizontal member extending between the same, vertical posts adjustably connected to said upper horizontal member, a lower horizontal member adapted to be cut into suitable lengths to extend between the fixed uprights and the 10 vertical posts adjacent their lower ends, an inverted U-shaped member secured at its

lower ends to said lower horizontal member and adjustably connected to said upper horizontal member, and a stanchion mounted within said U-shaped member and connected at its upper end thereto and at its lower end with said lower horizontal member, whereby said stall-end construction may be erected in spaces of varying widths between the fixed vertical uprights of the barn structure. 20 25

In testimony whereof I have hereunto set my hand this 11th day of March, 1912.

HENRY L. FERRIS.

In the presence of two subscribing witnesses.

D. L. WATTS,
R. A. HEMENWAY.
